PROTECTORS FOR ELECTRIC CIRCUITS

Frank H. Bussmann, Clayton, Mo., assignor to McGraw-Edison Company, a corporation of Delaware

Application January 14, 1955, Serial No. 481,776

7 Claims. (Cl. 200—154)

This invention relates to improvements in protectors for electric circuits. More particularly this invention relates to improvements in self-contained, manually-operable electric switches.

It is therefore an object of the present invention to provide an improved self-contained manually-operable electric switch.

In the operation of electric switches, it is essential that the switches be protected against prolonged arcing. Such arcing is very objectionable because it impairs or destroys the switches, and it can sometime cause fires. To prevent such prolonged arcing, manufacturers of electric switches have made those switches so they have a "snap-action" in opening the circuit. That "snap-action" is intended to separate the switch contacts so rapidly that arcs can not form; or if arcs should form, to lengthen those arcs so rapidly that they cannot be maintained but must extinguish themselves.

While a "snap-action" of the switch contacts is desirable in circuit-opening operations on direct current installations, a less-rapid action of the switch contacts is desirable in circuit-opening operations on alternating current installations. A very rapid opening of the switch contacts, such as is experienced in a "snap-action" circuit-opening operation, could be started and completed during either of the high voltage portions of a current cycle, and there would then be a strong tendency toward arcing. However, a less-rapid opening of the switch contacts would consume an amount of time that would enable the voltage to drop toward the zero value before the circuit-opening operation was completed; and there would then be a greatly lessened tendency toward arcing. The present invention utilizes this important principle to provide a self-contained manually-operable electric switch of greater reliability and less cost than has heretofore been possible. It is therefore an object of the present invention to provide a self-contained manually-operable electric switch that has a relatively slow circuit-breaking action.

The present invention has a movable contact and a fixed contact, and has a handle that is movable to cause movement of the movable contact. That handle is movable to an "on" position and to an "off" position; and it has a high point that moves through a dead center position as the handle moves from the "on" position to the "off" position. That high point moves the movable contact away from the fixed contact to open the circuit; and when that high point is in the dead center position it will hold the movable contact a considerable distance away from the fixed contact. This is very desirable since the handles of switches can sometimes, through inattention or inadvertence on the part of the operator, be set in the dead center position; and if the contacts were close together, when the handles were in the dead center position, arcing could occur. However, by having the high point of the handle hold the movable contact a considerable distance away from the fixed contact, whenever the high point is in the dead center position, the

present invention avoids any such arcing. It is therefore an object of the present invention to provide a switch with a movable contact and a fixed contact and with a handle that has a high point to hold the contacts apart a considerable distance whenever said handle is in the dead center position.

The movable contact of the switch provided by the present invention is a cantilever plate. That movable contact is biased toward a fixed contact by a helical compression spring. That spring is strong, and it urges the movable contact into engagement with the fixed contact at all times; and it will assure a low resistance engagement between the movable and fixed contacts whenever the handle is in the "on" position. However, the high point on the handle of the switch can overcome the force exerted by the spring. Hence, the switch that is provided by the present invention has a spring which directly biases the movable contact to circuit-closing position and has a handle that provides direct and positive circuit-opening movement of the movable contact. It is therefore an object of the present invention to provide a self-contained electrical switch which has a movable contact in the form of a cantilever plate that is biased toward a fixed contact by a helical compression spring and that can be moved to circuit-opening position by a handle.

Where electrical switches are small, they can sometimes be subjected to sufficient abuse to cause their parts to become separated from the housing. If those parts are electrically "alive," considerable danger can result, since the parts may cause arcing and sparking. The present invention ovates any such danger by providing a method of mounting the parts of the switch which positively prevents accidental separation of those parts from the housing. Specifically, the housing of the switch provided by the present invention, has formed guides into which the electrically "alive" parts extend; and it has openings through which the binding screws extend. Those openings are adjacent the closed end of the housing, and they will coact with that closed end and with the formed guides of the housing to prevent accidental separation of the electrically "alive" parts of the switch after those screws have seated in those parts. In this way, the switch can be assembled at the factory; and it will be resistant to the loss or separation of any of its parts. Only by removing the binding screws can electrically "alive" parts be removed; and those parts will not be "alive" when the binding screws are removed. In this way, the present invention positively prevents the freeing of electrically "alive" parts of the switch.

Other and further objects and advantages of the present invention should become apparent from an examination of the drawing and accompanying description.

In the drawing and accompanying description a preferred embodiment of the present invention has been shown and described but it is to be understood that the drawing and accompanying description are for the purpose of illustration only and do not limit the invention and that the invention will be defined by the appended claims.

60 In the drawing:

Fig. 1 is a perspective view of an electrical switch that is made in accordance with the principles and teachings of the present invention;

Fig. 2 is a longitudinal section of the switch shown in Fig. 1, and it is taken along the plane defined by the line 2—2 in Fig. 1;

Fig. 3 is another longitudinal section of the switch of Fig. 1 and it is taken along the plane defined by the line 2—2 in Fig. 1, and it shows the switch in open position;

70 Fig. 4 is another longitudinal section of the switch of Fig. 1 and it is taken along the plane defined by the

line 2-2 in Fig. 1, and it shows the component parts of the switch in dead center position.

Fig. 5 is a sectional plan view of the switch of Figs. 1-4, and it is taken along the plane defined by the line 5-5 in Fig. 2.

Fig. 6 is an end view of the handle of the switch of Figs. 1-5.

Fig. 7 is a perspective view of one of the terminals of the switch of Figs. 1-5.

Fig. 8 is a perspective view of a J-shaped element 10 used in the switch of Figs. 1-5, and

Fig. 9 is a perspective view of another terminal for the switch of Figs. 1-5.

Referring to the drawing in detail, the numeral 10 generally denotes a housing of insulating material. This housing will preferably be molded in one piece, but it can be fabricated if desired. The housing 10 has two vertically directed guiding projections 12 that are spaced from the right hand end wall of the housing 10 to define vertically directed recesses 14. Two vertically directed guiding projections 16 are spaced from the left hand end wall of the housing 10 to define two vertically directed recesses 18. The vertically directed guiding projections 12 and 16 extend all the way from the bottom of the housing 10 to the top of the housing, and thus the vertically directed recesses 14 and 18 also extend from the bottom of the housing 10 to the top of that housing. As a result, the housing 10 coacts with the vertically directed guiding projections 12 and 16 to define a large central recess and four smaller recesses at the corners of the housing 10.

A generally U-shaped shallow recess 20 is formed in the left hand end of the housing 10, and it is formed in the exterior face of that housing. An opening 22 extends through the left hand end wall of the housing 10 adjacent the upper end of the recess 20; and that opening communicates with the large central recess defined by the housing 10. A generally U-shaped recess 24 is formed in the right hand end wall of the housing 10 and it is formed at the outer face of that end wall. The recess 24 is closely comparable to the recess 20. An opening 26, which is closely comparable to the opening 22, extends through the right hand end wall of the housing 10 and communicates with the large recess at the interior of the housing 10. The openings 22 and 26 are in register with, and in alignment with, each other.

A frusto-conical projection or stud 28 is formed on the bottom of the housing 10 and it projects vertically upwardly into the central recess defined by that housing. This projection or stud is in register with the openings 22 and 26 in the left hand and right hand walls of the housing 10.

A pair of notches 30 are provided in the longitudinally extending side walls of the housing 10. These notches are in register with each other and are located approximately midway of the length of the housing 10. These notches are preferably U-shaped in configuration.

The numeral 32 denotes a plate of metal with a tab on the upper end thereof. The plate 32 is dimensioned so it fits snugly within the vertically-directed recesses 14 in the housing 10. The tab on the upper end of the plate 32 extends horizontally inwardly from the right hand end wall of the housing 10. An opening 34 is punched in the plate 32 and that opening is threaded to receive a binding screw 38. The plate 32 carries a contactor 36 on the tab thereof. This contactor coacts with the plate 32 to define a stationary contact and a stationary terminal for the switch of the present invention. The contactor 36 will preferably be made of a material which is resistant to arcing, and it will be made in the form of a disc with a central projection. The central projection will be extended upwardly through an opening in the tab on the plate 32 and will then be riveted over to hold it fixedly in assembled relation with the plate 32. The shank of the binding screw 38 is threaded and

will extend into and be held by the threaded opening 34. The head of the binding screw 38 is smaller than the recess 24 in the right hand end of the housing 10.

A short plate 39 of insulation is telescoped between the right hand end wall of the housing 10 and the vertically directed guiding projections 12. Thus, that plate will be held in the recesses 14 and will extend from the upper end of the plate 32 to the upper end of the housing 10.

The numeral 40 denotes a plate of metal which has a generally rectangular opening 42 through it. That plate also has an opening 44 punched through it and the opening 44 is threaded. A notch 46 is provided in the bottom of the plate 40 and that notch is spaced inwardly a short distance from each side of that plate. The plate 40 is dimensioned to fit into the recesses 18 defined by the left hand end wall of the housing 10 and the vertically directed projections 16. There is some looseness and play between the walls of the recesses 18 and the plate 40.

The numeral 48 denotes a J-shaped strip of flexible metal. That strip of metal has an opening 50 punched through it in the closed end of the J; and that opening will be slightly larger in diameter than is the opening 44 of the plate 40. A contactor 52 is fixedly secured to the long arm of the J-shaped strip 48 and that contactor will be made of an arc-resistant metal and will be suitably riveted to that long arm of the J-shaped strip 48. The numeral 54 denotes a binding screw and the shank of the screw can extend freely through the opening 50 of J-shaped strip 48 and seat in the threaded opening 44 of the plate 40. The head of the binding screw 54 is smaller than the recess 20 in the left hand end of the housing 10.

As pointed out particularly in Figs. 2-5, the J-shaped strip 48 is set against the left hand face of the plate 40 and the long arm of the J-shaped strip 48 extends through the opening 42 in the plate 40. Simultaneously, the short arm of the J-shaped strip 48 extends into and is confined by the notch 46 at the bottom of the plate 40. At such time, the opening 50 in the J-shaped strip 48 is in register with the threaded opening 44 on the plate 40. Consequently, the shank of the binding screw 54 can pass freely through the opening 50 and seat in the threaded opening 44 and thus secure the J-shaped strip 48 to the plate 40. At such time the long arm of the J-shaped strip 48 will extend toward the right hand end of the central recess defined by the housing 10. That long arm of the J-shaped strip 48 will be above and out of engagement with the top of the stud or projection 28. Also, the contactor 52 on the long arm of the J-shaped strip 48 will be below and directly in register with the contactor 36 on the tab of the plate 32. The long arm of the J-shaped strip 48 will normally hold the contactor 52 in engagement with the contactor 36, but that arm can bend downwardly to permit the contactors 52 and 36 to separate.

A strip of insulating material 55 in the form of a plate is disposed within the upper reaches of the recesses 18. That plate of insulation will extend from the upper end of the plate 40 to the upper end of the housing 10.

A helical spring 56 is mounted concentrically with the stud or projection 28, and that stud or projection will confine the spring 56 to the approximate center of the recess defined by the housing 10. The spring 56 will bear against the under side of the long arm of the J-shaped strip 48 and will urge that arm upwardly. Such upward movement of the long arm of the J-shaped strip 48 will normally hold the contactor 52 in engagement with the contactor 36. However, the spring 56 is yieldable and it can yield to permit downward movement of the long arm of the J-shaped strip 48 and the consequent separation of the contactors 52 and 36. The helical spring 56 has an axis which extends upwardly in a direction parallel to the axis of the stud or projection

28. The axis of the stud 28 extends through a line defined by the notches 30 in the housing 10.

A handle 58 is provided for the switch of the present invention, and that handle has a high point 59 thereon. When the handle 58 is in the "on" position shown in Fig. 2, the high point 59 is either out of engagement with the long arm of the J-shaped strip 48 or is loosely resting against that long arm. However, rotation of the handle 58 in a clockwise direction will bring the high point 59 almost immediately into engagement with the long arm of the J-shaped strip 48. That high point will then be moved to the dead center position shown in Fig. 4 and at that time the long arm of the J-shaped strip 48 will have been bent downwardly to move the contactors 52 and 36 apart. Continued rotation of the handle 58 in a clockwise direction will move the high point 59 to its final "off" position as shown in Fig. 3; and at such time the contactors 52 and 36 will be held apart.

The high point 59 is formed by two intersecting plane surfaces on the handle 58. Those plane surfaces are set so one of them is closely parallel to the long arm of the J-shaped strip 48 when the switch is in the "on" position, as shown in Fig. 2, and so the other plane surface is closely parallel to the long arm of the J-shaped strip 48 when the switch is in the "off" position, as shown in Fig. 3. This angular relationship between the plane surfaces that define the high point 59 is very desirable because it enables the spring-applied forces on the long arm of the J-shaped strip 48 to tend to hold the handle 58 in the "off" position as well as the "on" position. As a result, accidental movement of the handle 58 to either of its two positions is resisted.

The handle 58 is provided with oppositely disposed trunnions 60. Those trunnions are generally cylindrical in configuration, but they have a conical or fileted section which merges smoothly with the body of the handle 58. The cylindrical portions of the trunnions 60 extend into and are confined and supported by the notches 30 in the longitudinally extending side walls of the housing 10. The trunnions 60 interact with the notches 30 to permit guided and regulated rotation of the handle 58 relative to the housing 10.

A sheet 62 of fish paper is provided that overlies the upper end of the housing 10. This fish paper has an opening 63 through it to receive the handle 58. This fish paper will also overlie the upper end of the insulating plates 39 and 55.

A cover plate 64, preferably of metal, is provided for the housing 10. That cover plate has an opening 66 to receive the handle 58. The opening 66 is in register with the opening 63 in the sheet 62 of fish paper. The cover plate 64 has ears 68 that can be bent downwardly over projections at the opposite ends of the housing 10. The bending of the ears 68 over those projections will fixedly secure the cover plate 64 to the housing 10. During the assembling of the cover plate 64 with the housing 10, the cover plate will press the fish paper and the insulating plates 39 and 55 downwardly to confine and hold the plates 32 and 40 in register with the openings 22 and 26 in the opposite ends of the housing 10. The cover plate 64 also has threaded openings 70 which can receive screws that will hold the switch to a suitable mounting bracket, panel, plate or the like.

Once the cover plate 64 has been secured to the housing 10, the binding screws 38 and 54 can be telescoped into the threaded openings 34 and 44, respectively. During the assembly of the plates 32 and 40 with the housing 10, those binding screws had to be removed. Once they have been telescoped into the threaded openings 34 and 44 of the plates 32 and 40, those binding screws will positively prevent accidental separation of the plates 32 and 40 from the housing 10. The binding screw 54 will also prevent separation of the J-shaped lever 48 from the housing 10 as long as its shank is seated in the threaded opening 44 of the plate 40.

The interaction between the binding screws 38 and 54 and the plates 32 and 40 is very important in preventing the separation of "live" parts of the switch from the housing 10. If, through some unexpected accident the cover plate 64 were to become bent or broken and were to become separated from the housing 10, none of the electrically "live" parts could fall out of that switch housing. This is of great importance since it minimizes the risk of electrical shock and of electrical fires. Specifically, if the cover plate 64 were to become separated from the housing 10, the sheet 62 of fish paper could fall away from the housing and the plates 39 and 55 of insulation might fall away from that housing. However, the metal plates 32 and 40 and the J-shaped strip 48 could not fall away from the housing 10; the binding screws 38 and 54 positively preventing any such action.

In the "on" position shown in Fig. 2, the spring 56 is holding the movable contact in engagement with the fixed contact, and the high point 59 is at the right hand side of the dead center position shown in Fig. 4. In the "off" position shown in Fig. 3, the movable contact is spaced a predetermined distance from the fixed contact, and the high point 59 of the handle 58 is at the left hand side of the dead center position shown by Fig. 4. In the dead center position shown in Fig. 4, the movable contact is spaced from the fixed contact a distance closely similar to the distance those contacts are spaced apart in the "off" position shown in Fig. 3, and the high point 59 is in the dead center position. The fact that the spacing between the movable and fixed contacts in dead center position is closely similar to the spacing between those contacts in "off" position is important since it prevents prolonged arcing due to the movement of the handle into a dead center position where the fixed and movable contacts were closely adjacent each other.

It will be noted that the handle 58 drives the movable and fixed contacts apart as it rotates from "on" position to "off" position and that the spring 56 drives the fixed and movable contacts into engagement with each other as the handle moves in the opposite direction. Hence, the present switch gives a positive opening action and a spring-biased closing action. The result is that the switch provides a relatively slow circuit-breaking operation because the handle is having to oppose the strong helical spring 56 while it will provide a quick circuit making operation because that spring is then assisting the operator in rotating the handle to "on" position. The relatively slow circuit breaking operation is desirable because it allows the voltage of the alternating electrical current to fall toward the zero value and thus minimize arcing.

It will be noted that the high point 59 on the handle 58 is always relatively close to the dead center position shown in Fig. 4. This is desirable because it reduces the bending moments that would occur if the high point 59 were spaced a considerable distance from that dead center position. Those bending moments would not only be in the handle 58 but would also be in the long arm of the J-shaped strip 48.

The present invention relies upon the spring 56 to urge the contacts toward each other. That spring can be made quite strong since it need not carry current and since it occupies an otherwise empty portion of the recess within the housing 10. This is desirable since it makes unnecessary the provision of a springy metal in the J-shaped strip 48. That J-shaped strip will have some natural resilience and such resilience will help bias the contacts toward each other, but the principal circuit making force will be in the spring 56 and thus the J-shaped strip 48 can be made of a large number of metals rather than just of springy metals.

Whereas a preferred embodiment of the present invention has been shown and described it should be understood by those skilled in the art that various changes may be

made in the form of the invention without affecting the scope thereof.

What I claim is:

1. A manually operable electric switch that comprises a fixed contactor, a movable contactor that is movable relative to said fixed contactor, a helical compression spring, a handle that is selectively movable to "on" position and "off" position, a terminal that is secured to the said fixed contactor and is connectible to an electric circuit, a second terminal that is connected to said movable contactor and that is connectible to said electric circuit, said spring being intermediate and closely adjacent said terminals, said spring biasing said movable contactor toward said fixed contactor but being yieldable to permit said movable contactor to move away from said fixed contactor, said handle being movable to said "off" position to move said movable contactor away from said fixed contactor, a pivot for said handle, and a stud that is intermediate said terminals and that extends into and confines said spring and holds said spring out of shorting engagement with said terminals, said stud holding said spring so the axis of said spring extends toward said handle.

2. An electric switch that comprises a housing of insulating material, said housing having a closed side and an oppositely disposed open side, a plurality of contacts, grooves in said housing that extend from said open side to said closed side and that guide said contacts, said grooves permitting ready endwise movement of said contacts but preventing sideways or rotative movement of said contacts, and openings in said housing and in said contacts to receive binding screws, said openings in said housing being adjacent and contiguous with said closed side, said binding screws extending through said openings in said housing to seat in said openings in said contacts, said binding screws substantially preventing said endwise movement of said contacts and thereby coacting with said grooves and with said openings in said housing to prevent accidental separation of said contacts from said housing.

3. An electric switch that comprises a housing of insulating material having a closed side and an oppositely disposed open side, a plurality of contacts, grooves in said housing that extend from said open side to said closed side and that guide said contacts, said grooves permitting ready endwise movement of said contacts but preventing sideways or rotative movement of said contacts, and openings in said housing and in said contacts to receive binding screws, said binding screws extending through said openings in said housing to seat in said openings in said contacts, said binding screws substantially preventing said endwise movement of said contacts and thereby coacting with said grooves and with said openings in said housing to prevent accidental separation of said contacts from said housing.

4. A manually operable electric switch that comprises a fixed contactor, a movable contactor that is movable relative to said fixed contactor, a helical compression spring, a handle that is selectively movable to "on" position and "off" position, a terminal that is secured to the said fixed contactor and is connectible to an electric circuit, a second terminal that is connected to said movable contactor by an elongated strip of flexible metal, said second contactor being connectible to said electric circuit, said spring being intermediate and closely adjacent said terminals, said spring acting upon a portion of said elongated strip to bias said movable contactor toward said fixed contactor but being yieldable to permit said movable contactor to move away from said fixed contactor, said portion of said elongated strip being substantially straight, said handle being movable to said "off" position to move said movable contactor away from said fixed contactor, a pivot for said handle, and a stud that is intermediate said terminals and that extends into and confines said spring and holds said spring out of shorting engagements with said terminals, said stud holding said spring so the axis of said spring ex-

tends toward said handle, said substantially straight portion of said elongated strip enabling said spring to be substantially free of forces tending to produce sideways deformation of said spring as said handle is moved.

5. A housing having integral sides, bottom and ends, a flexible conductor that is substantially J-shaped in side elevation, the short leg and the closed end of said J-shaped conductor abutting, respectively, one end of said bottom and one of the ends of said housing, the long leg of said J-shaped conductor extending in a generally horizontal direction from said one end of said housing toward said opposite end of said housing, an L-shaped conductor in side elevation, said L-shaped conductor having the long leg thereof abutting said opposite end of said housing and extending upwardly from said bottom and having the short leg thereof extending from said opposite end of said housing toward said one end of said housing in a generally horizontal direction, said short leg of said L-shaped conductor overlying the free end of said long leg of said J-shaped conductor, a cover, and a handle that has a finger-receiving portion projecting outwardly from said cover and has a conductor-engaging portion underlying said cover and engageable with said long leg of said J-shaped conductor.

6. A housing having integral sides, bottom and ends, a flexible conductor that is substantially J-shaped in side elevation, the short leg and the closed end of said J-shaped conductor abutting, respectively, one end of said bottom and one of the ends of said housing, the long leg of said J-shaped conductor extending in a generally horizontal direction from said one end of said housing toward said opposite end of said housing, an L-shaped conductor in side elevation, said L-shaped conductor having the long leg thereof abutting said opposite end of said housing and extending upwardly from said bottom and having the short leg thereof extending from said opposite end of said housing toward said one end of said housing in a generally horizontal direction, said short leg of said L-shaped conductor overlying the free end of said long leg of said J-shaped conductor, a cover, and a handle that has a finger-receiving portion projecting outwardly from said cover and has a conductor-engaging portion underlying said cover and engageable with said long leg of said J-shaped conductor.

25 30 35 40 45 50 55 60 65 70

7. A housing having integral sides, bottom and ends, a flexible conductor that is substantially J-shaped in side elevation, the short leg and the closed end of said J-shaped conductor abutting, respectively, one end of said bottom and one of the ends of said housing, the long leg of said J-shaped conductor extending in a generally horizontal direction from said one end of said housing toward said opposite end of said housing, an L-shaped conductor in side elevation, said L-shaped conductor having the long leg thereof abutting said opposite end of said housing and extending upwardly from said bottom and having the short leg thereof extending from said opposite end of said housing toward said one end of said housing in a generally horizontal direction, said short leg of said L-shaped conductor overlying the free end of said long leg of said J-shaped conductor, a spring which biases said long leg of said J-shaped conductor toward said short leg of said L-shaped conductor, a cover, and a handle that has a finger-receiving portion projecting outwardly from said cover and has a conductor-engaging portion underlying said cover and engageable with said long leg of said J-shaped conductor.

8

7. A housing having integral sides, bottom and ends, a flexible conductor that is substantially J-shaped in side elevation, the short leg and the closed end of said J-shaped conductor abutting, respectively, one end of said bottom and one of the ends of said housing, the long leg of said J-shaped conductor extending in a generally horizontal direction from said one end of said housing toward said opposite end of said housing, an L-shaped conductor in side elevation, said L-shaped conductor having the long leg thereof abutting said opposite end of said housing and extending upwardly from said bottom and having the short leg thereof extending from said opposite end of said housing toward said one end of said housing in a generally horizontal direction, said short leg of said L-shaped conductor overlying the free end of said long leg of said J-shaped conductor, a spring which biases said long leg of said J-shaped conductor toward said short leg of said L-shaped conductor, a cover, and a handle that has a finger-receiving portion projecting outwardly from said cover and has a conductor-engaging portion underlying said cover and engageable with said long leg of said J-shaped conductor.

7. A housing having integral sides, bottom and ends, a flexible conductor that is substantially J-shaped in side elevation, the short leg and the closed end of said J-shaped conductor abutting, respectively, one end of said bottom and one of the ends of said housing, the long leg of said J-shaped conductor extending in a generally horizontal direction from said one end of said housing toward said opposite end of said housing, an L-shaped conductor in side elevation, said L-shaped conductor having the long leg thereof abutting said opposite end of said housing and extending upwardly from said bottom and having the short leg thereof extending from said opposite end of said housing toward said one end of said housing in a generally horizontal direction, said short leg of said L-shaped conductor overlying the free end of said long leg of said J-shaped conductor, a spring which biases said long leg of said J-shaped conductor toward said short leg of said L-shaped conductor, a cover, and a handle that has a finger-receiving portion projecting outwardly from said cover and has a conductor-engaging portion underlying said cover and engageable with said long leg of said J-shaped conductor, said conductor-engaging portion of said handle overcoming the bias due to said spring when said finger-receiving portion of said handle is in a predetermined position.
